Assistant Examiner — Giang Hoang Tran

(57) **CLAIM**

The ornamental design for a bicycle frame as shown and described.

DESCRIPTION

FIG. 1 is a right side elevation view of a bicycle frame showing my new design;

FIG. 2 is a left side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a top, front and left side perspective view thereof; and,

FIG. 8 is a top, rear and right side perspective view thereof. The broken lines in the drawings illustrate portions of the bicycle frame that form no part of the claimed design.

1 Claim, 6 Drawing Sheets
